UNITED STATES PATENT OFFICE

CLARENCE E. JACOBS, OF DETROIT, MICHIGAN

PROCESS OF MAKING OIL-PUMP SCREEN CAGES

Application filed September 23 1929. Serial No. 394,411.

The present invention relates to a process of making screen cages for oil pumps of motor vehicles engines and to the product of such process.

5 Among the objects of the invention is to greatly cheapen the production of such cages both by saving material and by simplifying the tools needed and their upkeep.

Other objects will readily occur to those skilled in the art upon reference to the following description and the accompanying drawing in which

Fig. 1 is a plan view of a blank in the first stage of the process.

15 Fig. 2 is an edge view of the same.

Fig. 3 shows the blank after the second step.

Fig. 4 shows the part punched out of the blank and its use as a second blank.

20 Fig. 5 shows the second punching.

Fig. 6 shows the final form of the part shown in Fig. 3.

Fig. 7 shows the final form of the part shown in Fig. 5, and

25 Fig. 8 shows a side view of a finished cage.

Fig. 9 illustrates a slightly different method of blanking out the outer spider when a very deep cage is required.

Fig. 10 illustrates the inner spider there-
30 for.

Figs. 11 and 12 show the spiders as formed for welding, and

Fig. 13 shows the finished deep cage.

As indicated, the process comprises first 35 stamping out of suitable sheet metal, discs 10 of a suitable size and forming upon these a narrow flange 11. These flanged discs are then, by means of a suitable punch, cut out to leave a flanged ring 10^a having inwardly 40 projecting radial tongues 12.

The punching 13 taken from the tongued ring is used as a blank from which to punch the spider 14, consisting of a central disc having outwardly extending radial tongues 15.

45 The ring 10^a is then, by means of a suitable die, formed as in Fig. 6, that is, the tongues 12 are bent down and curved inwardly as at 16 and each provided with a shouldered or stepped end 17.

50 The spider 14 is then also die formed to

the shape shown in Fig. 7; that is the tongues 15 are curved upward as at 18 on approximately the same radius as the tongues 16. At the same time, the disc portion of spider 14 is cupped inwardly as at 19 and provided with a central opening indicated by the dotted line 20 in Fig. 5.

When the parts 10^a and 14 have been so formed, the ends of tongues 18 are placed on the shoulders 17 and welded thereto as at 21, producing the form of cage shown in Fig. 8.

By producing the cage in the manner described, not only is there a great saving of material but the stiffness and strength of 65 the material is not impaired, such as will happen when such cages are produced by drawing out the cup portion prior to cutting away the metal, leaving the ribs, or by cutting away the metal, before drawing. 70 The ribs will have the same cross sectional area throughout due to the fact that they are stamped from a flat piece and merely bent to form.

Instead of cutting both spiders from the 75 same blank as described above, separate blanks may be used and thereby a deeper cage produced, if desired.

Fig. 9 for example, shows the spider arms 12^a as almost meeting at the center of the 80 blank, only a small square 12^b being cut out to separate them. Fig. 10 shows the other spider as produced from a separate blank and the arms 15^a limited in length 85 only by the size of the blank. After these pieces have been properly formed as indicated in Figs. 11 and 12, they are welded as indicated in Figs. 8 or 13 as at 21 to produce a cage similar to that of Figs. 1 to 8 but not limited in depth as above stated. 90

Now having described the invention and the preferred forms of embodiment thereof, it is to be understood that the said invention is to be limited, not to the specific details herein set forth, but only by the scope of the 95 claims which follow.

Claims:

1. The process of producing screen cages for oil pumps which comprises forming a disc, punching said disc to leave a ring hav- 100

- ing inwardly projecting radial tongues, cutting from the punched out portion as a blank a spider having outwardly extending radial tongues, bending downwardly the several tongues of the ring and fastening the ends of the first tongues to the ends of the second.
2. The process of producing screen cages for oil pumps which comprises forming a disc, punching said disc to leave a ring having inwardly projecting radial tongues, cutting from the punched out portion as a blank a spider having outwardly extending radial tongues, bending downwardly the several tongues of the ring and upwardly the tongues of the spider on approximately the same radius, and fastening the ends of the first tongues to the ends of the second.

CLARENCE E. JACOBS.
